UNITED STATES PATENT OFFICE.

THOMAS L. COWLES, OF BRIDGEPORT, CONNECTICUT, ASSIGNOR, BY MESNE ASSIGNMENTS, TO THE LOCOMOBILE COMPANY, OF BRIDGEPORT, CONNECTICUT, A CORPORATION OF DELAWARE.

DOOR CURTAIN FOR VEHICLES.

1,418,627.

Specification of Letters Patent. Patented June 6, 1922.

Application filed March 12, 1918. Serial No. 221,909.

To all whom it may concern:

Be it known that I, THOMAS L. COWLES, a citizen of the United States, and a resident of Bridgeport, county of Fairfield, and

5 State of Connecticut, have invented an Improvement in Door Curtains for Vehicles, of which the following description, in connection with the accompanying drawings, is a specification, like characters on the drawings representing like parts.

10 This invention relates to door curtains for vehicles, and is more especially concerned with a door curtain of the class in which the curtain constitutes an upward prolongation of the door, and is arranged to open and close therewith.

15 My invention will be best understood by reference to the following description, when taken in connection with the accompanying drawings of one specific embodiment thereof, while its scope will be more particularly pointed out in the appended claims.

In the drawings;

20 Fig. 1 is a side elevation of a portion of a vehicle body, having a folding "cape" top, and equipped with a door curtain embodying my invention;

25 Fig. 2 is a plan section taken on line 2—2 of Fig. 1; and shown at an enlarged scale;

30 Fig. 3 is a side elevation, partly in vertical section, of the door curtain supporting and re-inforcing means;

35 Fig. 4 is a front elevation of the curtain reinforcing means; and

Fig. 5 is an elevation, on a much enlarged scale, of the curtain view from the inner face.

Referring to the drawings, and to the embodiment of my invention which is illustrated therein, I have there shown a vehicle body 6, having a windshield 7, which supports a usual folding top 8. The body is provided with a usual door 9, which may be, and is herein, hinged at its rear edge.

40 A door curtain 10 closes a portion of the space between the upper edge of the body 6 and the lower edge of the top 8. This curtain may be, and is herein, prolonged rearwardly beyond the door 9, and may be secured to the body and to the top by appropriate means, such for example as a fastener 11, carried by the door, two fasteners 12 and 13 on the side of the body at the rear of the door, and two fasteners 14 and

15 on the top 8. These fasteners may be of any suitable character, but, as herein shown, are of the well-known turn-button type.

That portion of the curtain 10 which is above the door 9 constitutes an upward prolongation of the latter, and swings therewith during the opening and closing of the door.

To this end, there is provided reinforcing and supporting means, including a generally horizontal reinforcing and supporting member 16, and a generally vertical reinforcing and supporting member 17. The member

16 is herein provided with two arms 18 and 19, one of which extends lengthwise of the upper edge of the door, and the other transversely thereof, said arms being connected by a curved portion 20. The upper edge of the curtain is provided with a re-inforcing-member receiving-pocket 21, best

shown in Fig. 5, comprising a strip of suitable flexible material such as leather or fabric, sewn onto the curtain. Preferably, the rear end of the pocket is closed, as at 22,

and has an entrance at 23 for the introduction of the member 16, the latter being preferably provided with a rounded and somewhat pointed terminal portion 24, to facilitate its introduction into the pocket.

It should here be noted that the member 16 is suitably shaped as to the length of its arms 18 and 19 and the curve of the connecting portion 20, to correspond with the adjacent edge of the top 8, which overhangs the door 9 to a considerable extent at this point.

If desired, the top may be provided with a depending flap 25, arranged to overlie a portion of the upper edge of the curtain as shown in Fig. 1, to prevent the entrance of rain, snow or wind, at this point.

The member 17 is herein very irregular in shape, as best shown in Figs. 3 and 4, and comprises short and long generally upright portions 26 and 27, connected by a generally horizontal portion 28. The short upright portion 26 is supported in a suitable

socket 29 in the upper edge of the door 9, and may be held against turning movement in said socket in any suitable manner, as by providing said upright portion with a flat face 30, engaging a correspondingly-shaped portion of the socket 29.

The longer upright portion 27 is herein

2
provided with a reduced end 31, having a shoulder 32, while the arm 19 of the member 16 is provided with a correspondingly-shaped opening 33 to receive the same, as best shown in Fig. 2. By this means, the two members 16 and 17 are detachably secured to each other and to the curtain 10 in such a manner as to permit these parts to be entirely disconnected from one another, and stored more conveniently than is possible in a curtain in which the parts are incapable of being dismounted.

The current is preferably provided with a pocket 34, adjacent its front edge, to receive the longer upright portion 27 of the member 17, said pocket being preferably closed at its upper end as at 35, and having at its lower end an entrance 36 into which said member may be introduced. It should here be noted, by reference to Fig. 5, that the upper edge 20 of the curtain is longer than its lower edge, this being because the top 8 overhangs the door 9 to such an extent that the curtain must bend in an outward direction from the bottom to the top, as indicated in dotted lines in Fig. 4. If desired, the longer upright portion 27 of the member 17 may be curved outward and offset as at 37 to clear the side of the windshield 7, which usually 25 has an outward curve and offset from its point of attachment to the cowl of the body 6.

It should now be evident that the described 30 reinforcing and supporting members give to the curtain the necessary form and rigidity to make it fit the top and windshield of the vehicle, and to exclude the elements. When it is desired to remove the curtain and store the same away in a small space, this can 35 easily be done by unfastening the curtain at its various points of attachment to the body and top, and by lifting the member 17 from its socket in the door, after which the members may be withdrawn from their pockets 40 by first removing the member 17, and then removing the member 16. The two members may then be laid together in a very small space, and the curtain rolled into small compass, thus requiring very little storage space 45 in the vehicle.

While I have herein shown and described one specific form or embodiment of my invention for illustrative purposes, and have disclosed and discussed in detail the construction and arrangement incidental to one 50 specific application thereof, it is to be understood that the invention is limited neither to the mere details or relative arrangement of parts, nor to its specific embodiment herein shown, but that extensive deviations from the illustrated form or embodiment of the invention may be made, without departing from the principles thereof.

Having thus described my invention, what

I claim and desire by Letters Patent to secure is:

1. In a vehicle, the combination of a door, a door-curtain constituting an upward prolongation of said door, and door-curtain reinforcing means including a generally horizontal reinforcing member having two arms, one of which extends lengthwise of the upper edge of said door and the other transversely thereof, and a generally vertical reinforcing member having its upper end detachably secured to the transverse arm of said horizontal member.

2. In a vehicle, the combination of a door, a door-curtain constituting an upward prolongation of said door, said curtain being provided with a generally horizontal, reinforcing-member receiving-pocket and a generally vertical, reinforcing-member receiving-pocket the adjacent ends of said pockets 80 communicating with each other, and one having an entrance, and one of said pockets having another entrance, and curtain-reinforcing means including a generally horizontal, horizontally offset reinforcing member and a generally vertical reinforcing member having cooperating means detachably securing said members together, said members being insertable into and withdrawable from said respective entrances.

3. In a vehicle, the combination of a door, a door curtain constituting an upward prolongation of said door, said curtain being provided with a generally horizontal, reinforcing-member receiving-pocket and a generally vertical, reinforcing-member receiving-pocket the adjacent ends of said pockets communicating with each other, and one having an entrance, and one of said pockets having another entrance, and curtain-reinforcing means including a generally horizontal, horizontally curved reinforcing member and a generally vertical reinforcing member one having an opening and the other having means located in said opening detachably to secure said members together, said members being insertable into and withdrawable from said respective entrances.

4. In a vehicle, the combination of a windshield, a roof having a side laterally beyond said windshield, a body having a door, a door-curtain presenting an upward prolongation of said door, said curtain following said side and bending inward toward said windshield, and door-curtain reinforcing means carried by said door, said means including a generally horizontal member following said side and extending inward toward said windshield, and a generally vertical member, said members being detachable from each other and from said curtain.

5. In a vehicle, the combination of a windshield, a roof having a side laterally beyond said windshield, a body having a door, a door-curtain presenting an upward prolongation

gation of said door, said curtain extending forward from said door toward said windshield following said side and bending inward toward said windshield, and door-curtain reinforcing means carried by said door, said means including a generally horizontal member following said side and extending inward toward said windshield, and a generally vertical member having an offset forward of said door, said members being detachable from each other and from said curtain.

5. In a vehicle, the combination of a windshield, a roof having a side laterally beyond said windshield, a body having a door, a door-curtain presenting an upward prolon-

gation of said door, said curtain following said side and bending inward toward said windshield, and door-curtain reinforcing means carried by said door, said means including a generally horizontal member following said side and extending inward toward said windshield, and a generally vertical member extending forward from said door toward said windshield and sidewise to meet said horizontal member, said members being detachable from each other and from said curtain.

10. In testimony whereof, I have signed my name to this specification.

15. THOMAS L. COWLES.
